UNITED STATES PATENT OFFICE.

BALTZAR CARL VON PLATEN, CARL GEORG MUNTERS, AND SIGURD MATTIAS BÄCK-STRÖM, OF STOCKHOLM, SWEDEN, ASSIGNEES TO ELECTROLUX-SERVEL CORPORATION, OF NEW YORK, N. Y., A CORPORATION OF DELAWARE.

REFRIGERATION.

Application filed June 3, 1927, Serial No. 196,179, and in Sweden June 9, 1926.

Our invention relates to the art of refrigeration and relates particularly to that type of absorption refrigerating system wherein a constant total pressure is maintained throughout. It is the purpose of our invention to distribute refrigerative duty between several evaporators. In the preferred form, evaporation of the cooling agent (otherwise called refrigerant) takes place in an auxiliary agent, such as hydrogen gas. In accordance with a preferred form of the invention, more than sufficient cooling agent is supplied to one evaporator and the excess is evaporated in a secondary evaporator. The secondary evaporation may be used for cooling fluid within the system or for cooling substances outside the system. By our invention a complete evaporation of cooling agent is obtained and the refrigerative duty is distributed automatically due to the evaporation of the cooling agent in the auxiliary agent. Considering, for example, the auxiliary agent as hydrogen, the ability of ammonia to evaporate into hydrogen varies with different temperatures, increasing as the temperature rises. Thus, as one evaporator is given a greater load than another, the temperature of the auxiliary agent rises, and, as it rises more of the cooling agent evaporates into the auxiliary agent so that a greater refrigeration is produced. Thus a balance is obtained between a plurality of evaporators whereby high efficiency of distribution is obtained by the automatic operation of internal fluids of the system due to internal physical characteristics.

Another object of the present invention is the utilization of excess liquid refrigerant which would not otherwise evaporate. Still another object is to provide a refrigerator wherein separate compartments serve for refrigeration at different temperatures, more particularly one compartment for freezing ice and another for preserving food. These and other objects of the invention will be apparent from the following description taken in connection with the accompanying drawings on which:—

Fig. 1 shows more or less diagrammatically

an absorption system in which one form of the invention is embodied;

Fig. 2 shows another application of the invention wherein a different arrangement of parts is used;

Fig. 3 shows still another application of the invention wherein further heat exchange is provided;

Fig. 4 shows more in detail part of the apparatus shown in Fig. 3;

Fig. 5 shows a surface contact disk used in the absorption system; and

Fig. 6 shows still another application of the invention wherein two evaporators are used for cooling different external objects.

Referring more particularly to Fig. 1, reference character 1 designates a generator wherein is contained the refrigerant or cooling agent in solution in an absorbing liquid. For convenience in reference let it be assumed that the refrigerant is ammonia and the absorption liquid is water. Generator 1 is heated in any convenient way, as for instance, by the electrical resistance coil 9. The heat thus applied to the generator and its contents drives the ammonia out of solution. The gaseous ammonia passes upwardly through conduit 10 to the air-cooled rectifier or radiator 2 where any entrained water vapor is condensed and flows by gravity back to the generator. The ammonia vapor free from water passes into condenser 3 where it is cooled by cooling water or other means and is liquefied. The liquid ammonia flows downwardly through condenser 3 to the upper part of the primary evaporator 4 which is the regular or ordinary evaporator of the type of system dealt with in Patent No. 1,609,334 of December 7, 1926. An auxiliary agent, a gas inert with respect to ammonia, for instance hydrogen, also enters the top of the evaporator 4 through conduit 17. The ammonia diffuses into the hydrogen, producing refrigeration. Diffusion and evaporation in the evaporator are aided by disks 36 placed therein.

The mixture of ammonia and hydrogen formed in the evaporator has a greater specific weight than the relatively pure hydro-

gen which enters the evaporator at the top through conduit 17. Hence the mixture of gaseous ammonia and hydrogen and excess liquid ammonia that has not evaporated 5 passes downwardly through the evaporator 4 and through conduit 37 to a vessel 5 situated below primary evaporator 4 which will hereinafter be referred to as the secondary evaporator. Within the secondary evaporator 5 10 is a series of disks 39 which aid in the complete evaporation of the liquid ammonia which enters the vessel. This evaporation absorbs heat from hydrogen in vessel 14 as will be explained more fully later.

15 The gaseous mixture of ammonia and hydrogen passes out from the bottom of the secondary evaporator 5 through conduit 15 to the lower part of absorber 6. Absorption liquid which contains but little ammonia in 20 solution enters the top of the absorber 6 through conduit 11 and falls down over disks 40 placed within the absorber and comes in contact with the ammonia-hydrogen mixture. The ammonia is absorbed by the absorption 25 liquid and the hydrogen remains. This comparatively pure hydrogen is lighter than the ammonia-hydrogen mixture and passes upwardly through the absorber and through conduit 16 to the bottom of cooling vessel 14 30 and thence through conduit 17 to the top of the primary evaporator. Members 4, 37, 5, 15, 6, 16, 14 and 17 form a local cycle of circulation for hydrogen of which there is a 35 down-leg in the evaporators and conduit 37 and an up-leg in the absorber and conduit 17, the heavier specific gravity of fluids in the down-leg serving to cause continuous circulation in the local cycle. Vessel 14 is arranged in heat exchange relation with the secondary evaporator 5 and the hydrogen in 40 cooling vessel 14 is cooled by evaporation of ammonia in the secondary evaporator as it diffuses into hydrogen therein. Fins 13 are supplied on the secondary evaporator 5 to increase the rate of heat transfer from the 45 hydrogen. In order to prevent accumulation of water in vessel 14 which may be entrained with hydrogen passing through conduit 16, a small drain conduit 42 is connected between 50 vessel 14 and conduit 15. Water condensate in vessel 14 flows through conduits 42 and 15 into the absorber.

The absorption liquid which contains ammonia in solution passes out of the bottom of absorber 6 through conduit 12, a portion of 55 which is arranged as a coil 8 around the heating element 9 so as to form a thermo-siphon. This thermo-siphon causes the liquid to flow upwardly through conduit 12 from which it 60 is discharged into the upper part of the generator 1 at a level of liquid above that maintained in the absorber 6. In the generator the ammonia is driven out of solution as previously described and thus completes its cycle.

65 The absorption liquid flows downwardly

through the generator and through conduit 11 to the top of the absorber and thus its cycle is completed. This flow of the absorption liquid takes place because the thermo-siphon member 8 maintains a level of liquid in the generator above the point of discharge from conduit 11 into the absorber 6. Conduits 11 and 12 may be arranged in heat-exchange relation as indicated at 7 so that the hot liquid which comes from the generator will be cooled before it enters the absorber while at the same time the relatively cold liquid which comes from the absorber is heated before it enters the thermo-siphon. Cooling water for the absorber and condenser is supplied through conduit 50, passes through jacket 51, thence through conduit 52, through jacket 53 of the condenser and out through conduit 54.

It will be noted that it is the latent heat of vaporization of the ammonia which cools the hydrogen in vessel 14 rather than merely the heat of superheat which was previously used for this purpose as disclosed in the patent above referred to. By using the latent heat of vaporization, a greater cooling effect can be obtained than with merely transfer of the heat of gas.

Considering the members 4 and 5 as one combined unit, it might be said that the hydrogen passes in heat exchange relation with a portion of the outlet end of the evaporator before entering the evaporator. Conduit 37 constitutes a colder portion of the evaporator as a whole than the actual outlet end.

The cycles of operation of the apparatus shown in Fig. 2 are, in general, similar to those described above. Gaseous ammonia passes from the generator 1 through conduit 10 and rectifier 2 into condenser 3. The liquid ammonia which leaves the condenser divides, however, and a small proportion thereof flows through a narrow conduit 23 directly to secondary evaporator 5 while the remainder flows to evaporator 4. Evaporation of the ammonia takes place in the evaporator in the same manner as described in connection with Fig. 1. The ammonia-hydrogen mixture and any liquid ammonia that has not evaporated in its passage through the evaporator flows through conduit 20 to the top of secondary evaporator 5 where it joins the liquid ammonia which is here introduced through conduit 23. Secondary evaporator 5 is so constructed and arranged as to surround the upper part of absorber 6 and the lower portion of conduit 21 which conducts hydrogen from the upper part of the absorber to the upper part of the evaporator. Secondary evaporator 5 is provided with a series of baffle plates or disks 39. The liquid ammonia which enters secondary evaporator 5 through conduits 23 and 20 diffuses into and evaporates in the presence of the hydrogen in a manner similar to that previously described in connection with Fig. 1.

In Fig. 2, it will be seen that evaporation serves to cool the absorption liquid which enters the absorber as well as the hydrogen which leaves the absorber. This is accomplished partly by arranging conduit 11 to pass partly through secondary evaporator 5 and partly by transfer of heat from absorption liquid on the upper disks in the evaporator to the fluid within the secondary evaporator. Three fluids are here in heat exchange relation: (1) the mixture of ammonia and hydrogen; (2) liberated hydrogen; and (3) absorption liquid.

The ammonia-hydrogen mixture passes from secondary evaporator 5 through conduit 22 to absorber 6 where the ammonia is absorbed by the absorption liquid which has been cooled by the secondary evaporator. The hydrogen passes upwardly through the absorber and conduit 21 to the evaporator. The absorption liquid which contains ammonia in solution flows from absorber 6 through conduit 12 to generator 1 in the same manner as was described in reference to Fig. 1.

Likewise, in the apparatus shown in Fig. 3 the cycles of operation are substantially those described in relation to Fig. 1. Gaseous ammonia passes from generator 1 through conduit 10 and rectifier 2 to condenser 3. Liquid ammonia passes through conduit 24 to evaporator 4 where evaporation takes place in the presence of hydrogen as has been previously described. The mixture of gaseous ammonia and hydrogen together with liquid ammonia that has not evaporated leaves the bottom of the evaporator through conduit 34. A short distance from the evaporator, conduit 34 makes a sharp upward bend. Communicating with conduit 34 at this bend is conduit 31 through which the liquid and a portion of the gaseous ammonia-hydrogen mixture flows to the top of secondary evaporator 5. The remainder of the gaseous ammonia-hydrogen mixture passes upwardly through conduit 34 to the heat exchanger 18 wherein it flows downwardly through tubes 55 extending between tube heads 56 and absorbs heat from the hydrogen which passes upwardly through space 57 surrounding tubes 55. The mixture leaves the heat exchanger through conduit 35 and enters the absorber 6 where the ammonia is absorbed. A small drain hole 58 is provided in lower tube head 56.

The mixture of gaseous ammonia and hydrogen and liquid ammonia which passes through conduit 31 enters secondary evaporator 5 where the liquid ammonia evaporates and absorbs heat. One form of secondary evaporator which may be used is shown more in detail in Fig. 4. It has the form of a hollow cylinder on the inside of which is formed a spiral groove 80. The cylinder fits snugly over and is welded to conduit 30 and thus a

spiral path is provided in which the ammonia evaporates in the presence of hydrogen. The gaseous ammonia-hydrogen mixture passes through conduit 32 to conduit 35 through which it passes to the absorber.

The hydrogen, freed from its mixture with ammonia in the absorber, passes upwardly through the absorber to conduit 30. A portion of conduit 30 is within secondary evaporator 5 as described above and in this portion of the conduit the hydrogen is cooled by the evaporation of the ammonia in the secondary evaporator. The hydrogen is further cooled during its passage through heat exchanger 18. From heat exchanger 18 the hydrogen is introduced to the top of evaporator 4 through conduit 33.

The cycle of the absorption liquid between the absorber and generator takes place in the same manner as described in reference to Fig. 1 and Fig. 2.

Fig. 5 shows a preferred form of disk for apparatus hereinbefore described. The disk, which may be considered as disk 36 of Fig. 1, contains two passages, one for gas 60 and one for liquid 61. A low rim 62 surrounds passage 60 to allow a pool of liquid to accumulate and a higher rim 63 surrounds passage 60 to prevent liquid from flowing through the gas passage.

In Fig. 6 is shown a refrigerating apparatus wherein a primary and a secondary evaporator are placed in different compartments of a refrigerating cabinet. Reference character 75 designates a compartment particularly intended for making ice. Reference character 76 represents a compartment for cooling food and the like. The two compartments are separated by means of insulating material 78 and have separate doors for access thereto respectively. Primary evaporator 84 in compartment 75 is similar to evaporator 4 of the previous modifications. Secondary evaporator 85 in compartment 76 is similar to evaporator 5 of the previous embodiments. In this case, the primary evaporator is smaller than the secondary evaporator in order to obtain a proper proportion of surfaces of the evaporators for freezing ice and preserving food respectively. Surrounding the primary evaporator is a casting 70 which may be made of aluminum or like metal which may be bound to, or welded to, or soldered to, the evaporator in any suitable way. Casting 70 has a series of compartments 71 which are adapted to hold trays 72 for containing water to be made into ice. Secondary evaporator 85 is surrounded by a casting 73 which has a number of fins 74 for increasing the heat transmitting surface of the evaporator.

Freezing ice requires lower temperature than preserving food. If all the liquefied refrigerant were evaporated at the lower tem-

perature necessary for the production of ice, the efficiency of the apparatus would be lower than if some of the liquefied refrigerant is evaporated at higher temperature adequate for preserving food. In the arrangement herein described, only that part of the liquefied refrigerant necessary for the production of ice is evaporated at the low partial pressure causing this low temperature, while the part utilized for preserving food is evaporated at a higher partial pressure and higher temperature which makes it possible to have a high efficiency. In the primary evaporator a temperature of minus 10° to minus 13° centigrade can be maintained while a temperature of about minus 5° centigrade may be maintained in the secondary evaporator. Conduit 37 connecting the two evaporators is of relatively small size in order to minimize heat transfer from the secondary evaporator to the primary evaporator.

By means of this arrangement in a system employing an auxiliary pressure equalizing medium, the refrigerative load is distributed automatically between the evaporators due to the internal characteristics of the fluids without using automatic valves or the like. To illustrate, suppose that the primary evaporator contains ammonia and hydrogen. Suppose that the trays 72 contain water. When sufficient heat has been abstracted to completely freeze the water in trays 72, the temperature drops and as it drops the ammonia is less able to evaporate into the hydrogen. The temperature drops to a point where practically no further evaporation of the refrigerant will occur. At a temperature of minus 30° centigrade practically no evaporation is obtained. Therefore, substantially all the liquid refrigerant flows into the secondary evaporator and diffuses into hydrogen in the secondary evaporator, at which time the primary evaporator is automatically put out of service due to its low temperature. Heat introduced into either compartment, by opening the different doors of the two compartments, will be automatically and individually absorbed since an increase of temperature of either evaporator causes a greater amount of the refrigerant to evaporate quickly in the respective evaporators.

While we have described several forms of our invention, it is to be understood that we are not limited to the structures shown and described but that the invention is to be gaged by the scope of the prior art taken in connection with the appended claims.

Having thus described our invention, what we claim is:

1. Refrigerating apparatus of the absorption type comprising a generator, a condenser, a primary evaporator, a secondary evaporator, an absorber, said primary evaporator being positioned above said secondary evaporator, the evaporators being connected

in series, means to conduct vapor of a cooling agent from the generator to the condenser, means to conduct liquid cooling agent from the condenser to the primary evaporator, means to conduct an auxiliary agent in the presence of which the cooling agent evaporates from the absorber to the primary evaporator, means to conduct gaseous fluid from the secondary evaporator to the absorber whereby some of the cooling agent diffuses into the auxiliary agent in the primary evaporator at a relatively low temperature and some of the cooling agent diffuses into the auxiliary agent in the secondary evaporator at a relatively high temperature and means to circulate absorption liquid between the generator and absorber.

2. Refrigerating apparatus comprising a generator, a condenser, a primary evaporator of relatively small size, a secondary evaporator of larger size, a member adapted to freeze ice arranged in heat exchange relation with said primary evaporator, means for transmitting heat from surrounding atmosphere to said secondary evaporator, an absorber, means to conduct a vaporous cooling agent from the generator to the condenser, means to conduct liquid cooling agent from the condenser to the primary evaporator, conduits forming a cycle of circulation for an auxiliary agent in the presence of which the cooling agent evaporates through the absorber, the primary evaporator, the secondary evaporator and back to the absorber, one of said conduits being adapted to conduct liquid refrigerant from the primary evaporator to the secondary evaporator and means for circulating absorption liquid between the generator and absorber.

3. Absorption refrigerating apparatus of the type wherein a pressure equalizing medium is employed comprising a primary evaporator, a series of disks within said evaporator, a secondary evaporator situated below said primary evaporator, a series of disks in said secondary evaporator and means forming a restricted communication between the primary evaporator and the secondary evaporator.

4. Absorption refrigerating apparatus of the type wherein a pressure equalizing medium is employed comprising a primary evaporator, a series of disks within said evaporator for distributing liquid, a secondary evaporator situated below said primary evaporator, a series of disks in said secondary evaporator for distributing liquid, means forming a restricted communication between the primary evaporator and the secondary evaporator, an absorber, a conduit connecting said secondary evaporator with said absorber, a conduit connecting said absorber with said primary evaporator, a generator, means for circulating absorption liquid between said generator and said absorber and means to re-

ceive vaporous refrigerant from the generator, liquefy the same and conduct the liquid refrigerant to the primary evaporator.

5. Absorption refrigerating apparatus of 5 the type wherein a pressure equalizing medium is employed comprising a primary evaporator, a series of disks within said evaporator, a member surrounding said primary evaporator adapted to contain ice trays, a secondary 10 evaporator situated below said primary evaporator, a series of disks in said secondary evaporator, means forming a restricted communication between the primary evaporator and the secondary evaporator, means for 15 transmitting heat from surrounding atmosphere to said secondary evaporator, an absorber, means to conduct fluid from the lower part of said secondary evaporator to said absorber, means to conduct fluid from the upper part of said absorber to said primary evaporator, a generator, means to circulate absorption liquid between the generator and the absorber, a condenser, means to conduct vaporous refrigerant from the generator to 20 the condenser and means to conduct liquid refrigerant from the condenser to the primary evaporator.

6. That improvement in the art of refrigerating through the agency of a system employing an auxiliary agent in the presence of 30 which the cooling agent evaporates which consists in successively diffusing a portion of the cooling agent into the auxiliary agent in heat exchange relation with water to be converted into ice and the remainder of the cooling agent into the auxiliary agent at a higher temperature in heat exchange relation with surrounding atmosphere and isolating the portions diffusing at different temperatures.

40 7. That improvement in the art of refrigerating through the agency of a system employing an auxiliary agent in the presence of which the cooling agent evaporates which consists in successively diffusing a portion of 45 the cooling agent into the auxiliary agent in heat exchange relation with water to be converted into ice and the remainder of the cooling agent into the auxiliary agent at a higher temperature in heat exchange relation with surrounding atmosphere and isolating the portions diffusing at different temperatures by restricting flow of fluid between the space of low temperature diffusion and the space of high temperature diffusion.

55 8. That improvement in the art of refrigerating through the agency of a system employing an auxiliary agent in the presence of which the cooling agent evaporates which consists in successively diffusing portions of 60 the cooling agent into the auxiliary agent in a plurality of substantially isolated spaces at different temperatures and varying the rate of diffusion in the spaces in accordance with variations in temperature of the auxiliary agent.

9. A refrigerator comprising a plurality of compartments, heat insulating material separating the compartments, a primary evaporator situated in one compartment, a secondary evaporator situated in another compartment, said primary evaporator being smaller than said secondary evaporator, ice forming means in heat exchange relation with the primary evaporator, the compartment containing the second evaporator being adapted to contain food, a conduit connecting the primary evaporator with the secondary evaporator passing through the heat insulating material, an absorber, a generator, a condenser, means to conduct vaporous cooling agent from the generator to the condenser, means to conduct liquid cooling agent from the condenser to the primary evaporator, means to circulate an auxiliary agent, in the presence of which the cooling agent evaporates, through the evaporators in series and through the absorber and means to circulate absorption liquid between the generator and absorber.

10. A refrigerator comprising a plurality of compartments, heat insulating material separating the compartments, a primary evaporator situated in one compartment, a secondary evaporator situated in another compartment, a conduit connecting the primary evaporator with the secondary evaporator passing through the heat insulating material, an absorber, a generator, a condenser, means to conduct vaporous cooling agent from the generator to the condenser, 95 means to conduct cooling agent from the condenser to the primary evaporator, means to circulate an auxiliary agent, in the presence of which the cooling agent evaporates, through the evaporators in series and through 100 the absorber and means to circulate absorption liquid between the generator and absorber.

11. A refrigerator comprising a plurality of compartments each having separate doors, 110 heat insulating material separating the compartments, a primary evaporator situated in one compartment, a secondary evaporator situated in another compartment, a series of disks in each of such evaporators for distributing liquid within the same, said primary evaporator being smaller than said secondary evaporator, ice forming means in heat exchange relation with the primary evaporator, the compartment containing the secondary evaporator being adapted to contain food, means for transferring heat from surrounding atmosphere to the secondary evaporator within the food compartment, a conduit connecting the primary evaporator with the secondary evaporator passing through the heat insulating material, said primary evaporator being positioned above said secondary evaporator and the connecting conduit being adapted to permit flow by gravity of 115 120 125 130

liquid therethrough, a generator, a condenser, means to conduct vaporous cooling agent from the generator to the condenser, means to conduct cooling agent from the condenser to the primary evaporator, means to circulate an auxiliary gas, in the presence of which the cooling agent evaporates, through the evaporators in series and through the ab-

sorber and means to circulate absorption liquid between the generator and absorber. 10

In testimony whereof we have hereunto affixed our signatures.
